UNITED STATES PATENT OFFICE.

ELZA T. S. CLIFFE, OF MANSFIELD, OHIO.

AUTOMATIC DELIVERY SYSTEM.

1,351,413.

Specification of Letters Patent. Patented Aug. 31, 1920.

Application filed January 10, 1919. Serial No. 270,456.

To all whom it may concern:

Be it known that I, ELZA T. S. CLIFFE, a citizen of the United States of America, residing at Mansfield, in the county of Rich- 5 land and State of Ohio, have invented cer- tain new and useful Improvements in Auto- matic Delivery Systems, of which the fol- lowing is a specification, reference being had therein to the accompanying drawings.

10 The objects of my invention are to pro- vide an automatic parcel and safe delivery system that is electrically operated for auto- matically conveying parcels and freight from a central station to a sub-station, and 15 to provide a system which may be con- veniently installed underground in large cities and above ground for rural delivery.

Other objects of my invention are to pro- 20 vide an automatic trolley system of the above type wherein the cars or trains are suspended from trolley wires or rails and the cars or trains drawn by motor cars set in motion at a central station and auto- matically controlled by a sub-station, and 25 to furnish such a system with sub-stations for receiving parcels and freight without injury or damage to the same.

Further objects of my invention are to 30 provide a delivery system of the above type wherein the suspended cars or carriers automatically control switching or shunting of a train of cars from one path of travel to another, such being established without any danger of the train of cars being de-railed 35 or side wiping any train *en route*; and, to furnish cars of such a system with novel automatic brakes that are applied to the wires or rails from which the cars are sus- pended.

40 Still further objects of my invention are to provide a system of the above type which on a small scale may be installed in large buildings for conveying parcels and other matter from one floor to another and to sta- 45 tions on the floors; and, when constructed on a large scale is operated throughout the country as an auxiliary to the mail order business, thus permitting a purchaser to obtain prompt delivery of any matter, with- 50 out the employment of labor incident thereto.

The above are just a few of the many ob- jects and advantages derived from a system 55 in accordance with my invention, and refer- ence will now be had to the drawings show-

ing a preferred embodiment of my invention, but it is to be understood that the structural elements shown and hereinafter described are merely an example of me- chanical devices that may be used for carry- 60 ing my invention into practice.

In the drawings,

Figure 1 is a side elevation of a portion of the trolley system, particularly adjacent a switch; showing the mechanism for auto- 65 matically switching or shunting a train of cars;

Fig. 2 is a plan of the same;

Fig. 3 is a detail view of a portion of the trolley pole and trolley wire or rail bracket; 70

Fig. 4 is a detail front elevation of a por- tion of the switch operating mechanism;

Fig. 5 is a horizontal sectional view of a receiving station;

Fig. 6 is a vertical sectional view of the 75 same, showing a car in side elevation rela- tive thereto, and about to deposit matter in the receiving station;

Fig. 7 is an end view of a parcel or freight car; 80

Fig. 8 is a side elevation of a portion of a motor car showing the trolley suspension thereof;

Fig. 9 is a side elevation of a parcel or freight car, partly broken away and partly 85 in section, showing in particular the brakes associated therewith;

Fig. 10 is a bottom plan of a car with the doors thereof closed;

Fig. 11 is a horizontal sectional view of a 90 motor car showing the motor and controlling mechanisms therein, and

Fig. 12 is an end view of the same.

Along the right of way are sets of prop- erly spaced trolley poles 1 provided with 95 insulated brackets 2 supporting parallel trol- ley wires or rails 3, and these wires or rails are of sufficient strength to permit of con- siderable weight being suspended from the same. The wires or rails 3 may be con- sidered as an overhead track and before con- sidering the cars suspended therefrom, ref- erence will be had to Figs. 1, 2 and 4 show- 100 ing a switch that is automatically actuated for shunting a train of cars on to a branch track or siding 4. The main track 3 has a severed section 5 that may be flexed or swung to align with the end of the branch track, somewhat similar to switch tongues and to automatically accomplish an opera- 105 110

tion of the switch, the following mechanism is employed.

Below the main track 3 and contiguous to the flexible section 5 thereof is located a pedestal 6 provided with bearings 7 and a bracket 8. Journaled in the bearings 7 is a longitudinal shaft 9 having a worm 10 meshing with a horizontally disposed gear wheel 11 rotatable on the top of the pedestal 6, and said gear wheel is provided with a radially disposed stop arm 12 and an angularly disposed trussed switch arm 13 said arm having the upper end connected to the ends of the flexible section 5 of the main track 3, so that when the gear wheel 11 is partially rotated the end of the main track 3 may be flexed to align with the branch track 4. The radially disposed arm 12 extends into the bracket 8 and by contacting with the bracket limits the movement of the switch arm 13.

Adjacent the pedestal 6, at the sides of the main track 3, is an A frame 14 extending in proximity to one of the wires or rails of the main track and slidable in said A frame is a vertically disposed rack rod 15 which has its upper end provided with a bracket or support 16 for one of the wires or rails of the main track. The lower end of the rack rod 15 telescopes with a pedestal 17 and contains a coiled compression cushion spring 18 adapted to restore the rack rod 15 to an elevated position after said rod is depressed by the weight of train or car on the main track 3 above the bracket or support 16. The lower telescoping end of the rack rod 15 has a rack 19 meshing with a pinion 20 on the shaft 9, said shaft being journaled in a bearing 21 forming part of the pedestal 17. The bearing 21 affords a support for a spring pressed latch 22 that engages under the lower end of the rack rod 15 and holds said rack rod normally elevated, so that said rack rod cannot be depressed until the latch 22 is withdrawn. To accomplish this, said latch is connected to a cable or flexible connection 23 extending under a sheave carried by one of the trolley poles 1, said cable extending upwardly to a pivoted bell crank 24, carried by the bracket 25 on the trolley pole 1.

The rack rod 15 is located a sufficient distance from the flexible section 5 of the main track so that the switch may be operated in sufficient time for a train or car to move on to the branch track 4, and it is essential that the switch arm 13 firmly support the flexible section in order that there may be no sagging movement of said section due to the weight of a car. With the flexible section 5 shiftable in a horizontal plane, the inherent tendency of the wires or rails of the main track to assume normal position will coöperate with the expansive force of the spring 18 in returning the flexible section of

the main track to its normal position after a train has passed on to the side branch 4.

It is also essential that the rack rod 15 be located intermediate two sets of trolley poles 1, so that one of the wires or rails of the main track may be sufficiently flexed to lower the rack rod 15 and actuate the switch. The bell cranks 24 may be of different lengths and placed in different positions, so as to differentiate the various switches of the system, and with a train or cars moving in the direction of the arrow A of Fig. 1, the bell crank 24 is adapted to be tripped or actuated so as to withdraw the latch 22 and permit of the weight of a car or train actuating the switch when it is desired to pass on to the branch track 4.

Considering the motor car adapted for drawing a train of cars, reference will be had to Figs. 8, 11 and 12 showing a box-like car body 26 having sets of hangers 26^a and 27 connected by longitudinal frames 28. The sets of hangers 26^a and 27 are insulated from the car body 26 and journaled in the upper ends of said hangers are grooved trolley wheels 29 that travel on the wires or rails of the tracks 3 or 4. The trolley wheels 29 are preferably of two sizes and the large set of trolley wheels are mounted on shafts 30 having sprocket wheels 31 over which are trained sprocket chains 32 that extend through the roof of the car body 25 and are trained under sprocket wheels 33 on the ends of an armature shaft 34 forming part of an electric motor 35 within the car body 26. The electric motor 35 is electrically connected, as at 36, to one of the hangers 26^a, and one of the hangers 27 is connected, by a conductor 37, to an automatic cut out switch 38, said cut out switch being connected by a conductor 39, to a manually operated knife switch 40 that is in turn connected, as at 41, to the motor 35.

Adjacent the automatic cut out switch 38 is a bracket 42 supporting a pivoted switch arm 43 that serves the automatic switch 38, said switch arm having one end thereof connected by a link 44 to an automatic switch closing rod 45 supported in suitable bearings 46, the rod 45 is encircled by a spring 66 that bears against a collar 46^a on the rods and maintains the switch arm 43 normally closed.

The opposite end of the switch arm 43 has a cam shoe 47 engaging a ball bearing 48 on the end of a transverse shiftable shaft 49 mounted in bearings 50 and 51, the latter containing a coiled compression spring 52 that maintains the ball bearing 48 normally in engagement with the cam shoe 47 of the switch arm 43.

On the shiftable shaft 49 and fixed for rotation therewith are gear wheels 53 and 54, the former being beveled and adapted to mesh with the beveled face 55 of a gear 130

wheel 56 supported in bearings 57, said gear wheel meshing with a large gear wheel 58 on the armature shaft 34 of the motor 35.

The gear wheel 54 is adapted to be rotated by a motor braking or retarding mechanism, which in its present form, consists of an incased large band spring 59 having its arbor geared as at 60, to a longitudinal shaft 61, journaled in bearings 62. The longitudinal shaft 61 imparts movement to beveled gear wheels 63 and one of said beveled gear wheels is on the face of a gear wheel 64 with which the gear wheel 54 is adapted to mesh.

On the longitudinal shaft 61 is a cam arm 65 and when the longitudinal shaft 61 makes one revolution, the cam arm 65 impinges against the face of the gear wheel 54 and shifts the shaft 49 to a retracted position, as shown in Fig. 11.

As shown in Fig. 11, the motor car may be considered as in operation, as the automatic shut off switch 38 is closed, also the manually operated blade switch 40, closing the circuit of the electric motor 35 and thus causing said motor to impart movement to the large trolley wheel 29, which causes the motor car to travel on the overhead track.

The switch arm 43 is connected by a link and universal connection 44^a to a crank wheel 43^a of a controlling motor 50^a, said motor being operated from a storage battery 51^a or from the main source of electrical energy, and when said motor is started, the wheel 43^a and linkage 44^a open and break the circuit through the electric motor 35.

As the switch arm 43 is swung to an open position, the transverse shaft 49 is shifted placing the gear wheel 54 in mesh with the gear wheel 64 and the beveled gear 53 in mesh with the beveled gear 55. With the spring 59 normally unwound, the overrunning movement of the electric motor 35 is retarded by the spring 59 being placed under tension and this has a restraining influence on the motor that causes the same to stop whereby a train or car will not be carried past a predetermined designation. By the time there is a cessation in the operation of the motor 35, the transverse shaft 49 has

made a complete revolution causing the cam arm 65 to impinge against the face of the gear wheel 54 and thus coöperate with the spring 52 in restoring the transverse shaft 49 to normal position, causing the switch arm 43 to close and start the motor 35.

When the gear wheels 54 and 64 are dis-engaged the spring 59 assumes a normal unwound position. It is now apparent that the elements 47 to 65 inclusive constitute means for braking or retarding the electric motor after the electric circuit is broken through the same, and the starting and stopping of said motor is automatically controlled by the controlling motor 50^a as will hereinafter appear.

Besides the motor car being utilized as a tractor or propulsion means for a train, said motor car is equipped to operate the switch throwing mechanism shown in Fig. 1.

One of the hangers 27 is provided with a bracket 67 for an adjustable trip 68, which is set in the path of the bell crank 24, so as to impinge against said bell crank and trip the same to permit of the switch being thrown as shown in Fig. 2.

Considering the parcel or freight cars, one of which is illustrated in Figs. 6, 7 and 9, and 10, said car comprises a rectangular body 69, and extending upwardly from the sides of the body are sets of hangers 70. The upper ends of the hangers 70 are provided with universal joints 71 connecting said hangers to trolley harps 72. In the harps 72 are revoluble trolley wheels 73 and 74, the former riding on the wires or rails of the main track, and the latter riding against said wires or rails with said wheels coöperating in preventing accidental displacement of the trolley harps.

The bottom of each car body is formed by inclined end walls 75 to facilitate the discharge of a parcel or full load and by hinged drop doors 76 and 77, which when released discharge the contents of the car body. The drop doors 76 and 77 are hinged to the side walls 78 of the car body by strap hinges 79 and associated with said hinges are coiled retractile springs 80 adapted to automatically close the doors 76 and 77 after said doors have been opened by a load to discharge the same.

On the bottom of the door 76 are pivoted latch bars 81 adapted to engage in keepers 82 of the door 77 and thus lock the door in a closed position. Connecting the pivoted latch bars 81 is a longitudinal slide bar 83 supported in straps 84 connected to the door 76. Connected to one end of the slide bar 83 is a coiled retractile spring 85 which is connected to the door 76 and is adapted to shift the slide bar 83, when said bar is released, to swing the latch bars 82 to an open position. The opposite end of the slide bar 83 terminates in a beveled tooth 86 engaged by a bell crank latch 87 pivotally connected to a bracket 88, carried by one of the inclined end walls 75 of the car body 69.

Journaled in the side walls 78 of the car body, at the forward end thereof, is a rock shaft 89 provided with a crank 90 connected by links 91 to the bell crank 97. Adjacent the crank 90 is another crank 100 connected by a retractile spring 92 to the car body. The crank 100 serves as a switch arm and is adapted to close a controlling switch 93 carried by a bracket 94 on the end wall 75 of the car body 69. Wires 95 connect said switch to train wires 96^a extending through conduits 97^a adjacent one of the side walls 78 of the car body, so as not to interfere 130

with the discharge of merchandise from the car body. The train wires 96^a extend out of the ends of the car body and are adapted to have the ends thereof connected to the train wires of other cars by plugs and coupling wires, generally designated 98^a.

The ends of the rock-shaft 89 outside of the car body 69, are provided with cranks 96 connected to upwardly extending brake rods 97. The upper ends of the brake rod 97 are yieldably connected, as at 98, to pivoted levers 99 supported by one set of the trolley harps 72, and these pivoted levers support the rotatable trolley wheels 74 of said harp, 15 so that a rocking movement of the shaft 89 will raise or lower the trolley wheels 74 relative to the wires or rails of the overhead track. It is therefore possible to rock the shaft 89 and cause the trolley wheels 74 to 20 have a braking action against the wires or rails to retard the movement of the car. The shaft 89 may be rocked while the car is in motion, by the depending crank 100 being shifted or actuated at a station where 25 parcels or freight is to be delivered.

Coupling members 101, of one car are adapted to be connected to the members of an adjoining car when coupling the train wires 96^a.

Reference will now be had to Figs. 5 and 6 showing a receiving station, which may be in the form of a metallic structure having parallel side walls 102, a rear wall 103, and an inclined front wall 104. This metallic structure will afford an elevator well or way and the lower end of said structure may be supported in a suitable foundation 105 having a door and doorway 106 registering with a doorway 107 in the lower end of the 40 station structure.

The inner sides of the walls 102 have vertical guideways 127 for the guides 108 of a boxlike elevator 109, said elevator having side frames 110 provided with wheels 111 bearing against the rear wall 103 of the station structure.

The bottom of the elevator 109 has a dashpot 112 containing a spring pressed piston or plunger 113, that extends out of 50 the dashpot and is provided with a wheel 114 to ride against the inner side of the inclined front wall 104. The dash pot 112, is apertured, as at 116, and is provided with a suitable check valve 115, and in consequence of this dash pot the descent of the elevator 109 will be retarded by the inclined front wall 104 of the station structure. The extreme lowering movement of the elevator is also retarded by buffers or cushions 117 55 on the bottom of the station structure, and to raise the elevator a weight 118 is employed. This weight is in a well 119 at the rear side of the station structure and is attached to a cable 120 guided by a sheave 121 60 and trained over another sheave 122 sup-

ported from a funnel or chute 123 on the top of the station structure. The cable 120 is attached to a bracket 124 of the elevator 109 and the weight 118 serves as a counter-balance to coöperate with the dashpot in 70 preventing too sudden a descent of the elevator when loaded.

The funnel 123 is adapted to have a car or train of cars pass thereover, and said funnel or chute has a support 125 for an 75 adjustable trip 126 adapted to be engaged by the depending crank 100 of the car.

In practice and with the system, installed above ground, the overhead track is a sufficient distance above the ground so that the 80 train will not interfere with traffic, and it is preferable, if not actually necessary, to provide the receiving station so that merchandise may be delivered without an attendant at the station. The elevators or gravity 85 carriers not only convey the merchandise from an elevation to a point where it may be conveniently obtained but prevents the merchandise from being injured or broken when deposited at a receiving station. 90

Assuming that a train has been loaded at a central station and one car consigned to John Doe and another to James Roe. These gentlemen have the trips 126 constantly set at their receiving stations, so 95 that when the cars of the consignor reaches the different stations the contents of the cars will be deposited. The crank 100 of the car load intended for John Doe is also set to impinge against the trip 126 and these elements of the car consigned to James Roe are set in different vertical planes from those of John Doe, so that each consignee will receive proper goods.

When the car reaches the receiving station of John Doe the shaft 89 is rocked, and three distinct operations result from such actuation of the shaft. First, the latch bell crank 87 is actuated to release the drop doors 76 and 77 so that the contents of the 110 car may drop into the chute 123 and the elevator 109 of the receiving station structure. The doors 76 and 77 are snapped shut and automatically locked.

Next, the rocking movement of the shaft 115 89 imparts movement to the brake rods 97 and the trolley wheels 74 are actuated to bear against the wires or rails and retard the movement of the train. Simultaneously with this operation the switch 93 is closed, and the controlling motor 50^a started to open the switch arm 43 and break the circuit of the motor 35 in the motor car. The operation of the motor is retarded by brake or restraining mechanism of said car. In other 120 words, the train is brought to a standstill as soon as possible so that the car intended for John Doe may deposit the merchandise in the service station for John Doe.

As the discharge of the merchandise is 130

almost instantaneous, the cessation in the 5 operation of the motor 35 is for a very short period, as the spring 66 restores the switch arm 43 to normally closed position, closing the circuit of the motor 35 and setting the train in motion. When the crank 100 is restored to normal position, the brake mechanism of the track is released and the train may proceed to the receiving station of 10 James Roe, where the merchandise in another car intended for James Roe is deposited in his receiving station.

It is through the medium of the branch 15 track that merchandise may be delivered from a main line direct to a rural residence and instead of the cars directly returning to the station from which said cars are started, the cars may travel to a rural station and be loaded with products to be delivered in 20 a city or to another station. The cars may have top or side doors so as to be conveniently loaded, and since the cars are not subjected to violent vibrations, stresses or strains, said cars can be made comparatively 25 light in weight, so that when loaded, the overhead wires or rails will readily support the same.

What I claim is:

1. In a delivery system, the combination 30 of an overhead track, a flexible switch section, means below said track adapted for flexing said switch section, cars suspended from said track, motive power for said cars,

and means movable with said car adapted to actuate said switch flexing means. 35

2. In a delivery system, the combination 40 of an overhead track having a flexible switch section, a switch arm actuated by depressing a portion of said track to flex said switch section, means normally supporting the portion of said track adapted to be depressed, a car adapted to travel below said track, and means carried by said car adapted to release 45 said track supporting means so that the weight of said car may depress the track portion to actuate said switch arm.

3. In a delivery system, the combination 50 of overhead parallel wires having a flexible switch section, a car suspended from said wires, and means actuated by the weight of said car on said wires adapted to flex the switch section of said wires.

4. In a delivery system, the combination 55 of overhead parallel wires having a flexible switch section, a car suspended from said wires, a switch arm connected to the switch section of said wires to flex said section, and means adapted to be shifted by the weight of the car on one of said wires to operate 60 said switch arm.

In testimony whereof I affix my signature in the presence of two witnesses.

ELZA T. S. CLIFFE.

Witnesses:

CHARLES W. CHEW,
DR. TALBUT.
